ARM SPLINT

George E. Moore II, Hollywood, Fla., assignor to
All Orthopedic Appliances, Inc., Miami, Fla.

Filed Feb. 14, 1974, Ser. No. 442,646

Term of patent 14 years

Int. Cl. D24—04

U.S. Cl. D83—1 J

FIG.3

FIG.1

FIG.2

FIG. 1 is a top plan view of an arm splint showing my new design;

FIG. 2 is a bottom plan view; and

FIG. 3 is a perspective view of my arm splint as positioned on a person which is shown in dotted lines for illustrative purposes only.

I claim:

The ornamental design for an arm splint, substantially as shown and described.
